By his Atty.
Henry Williams.

UNITED STATES PATENT OFFICE.

PELEG S. BRADFORD, OF BRIDGEWATER, MASSACHUSETTS.

FOLDING CRANK FOR EXTENSIBLE LADDERS.

SPECIFICATION forming part of Letters Patent No. 399,313, dated March 12, 1889.

Application filed December 13, 1888. Serial No. 293,513. (No model.)

To all whom it may concern:

Be it known that I, PELEG S. BRADFORD, of Bridgewater, in the county of Plymouth and State of Massachusetts, have invented new 5 and useful Improvements in Folding Cranks for Extensible Ladders, of which the following is a specification.

In the accompanying drawings, in which similar letters of reference indicate like parts, 10 Figure 1 is a side elevation of any extensible ladder closed and provided with my improved crank. Fig. 2 is a central vertical section of the same partially raised or extended. Fig. 3 is a sectional detail of the crank.

15 A represents the lower ladder-section, B the central section, and C the upper. The lower section, A, is provided near its upper end with clamps *a*, (not new in this invention,) secured to said section, and bent around the 20 edges of the rails of the section B, which is adapted to slide up and down therein. Secured to the lower end of the section B are similar clamps, *b*, which bend around the edges of the rails of section A.

25 *c c* represent two pairs of clamps placed one pair above the other, secured to the upper portion of section B, and bending around the edges of the rails of section C.

30 D D are swinging legs for supporting the ladder, pivotally secured at their upper ends to the upper portion of the section A.

E is a barrel or drum fixed upon the shaft *e*, supported by the section A, and whose end is squared to receive a crank.

35 F is a rope, or the mechanical equivalent thereof, secured at its lower end to the drum or barrel E, passing over a pulley, II, suspended from the cross-piece A', supported by the upper ends of the rails of the section A, 40 and secured at its other end to one of the rungs (preferably the lowest) in the section B.

I is a rope, or the mechanical equivalent thereof, secured at one end to the cross-piece A', passing up over the pulley J, which is suspended from a cross-piece, B', secured to and supported by the upper ends of the rails of the section B, and down to one of the rungs (preferably the lowest) of the section C, to which its other end is secured.

45 Now, if a crank be applied to the shaft *e*, the rope F will cause the section B to slide

up on the section A, and at the same time the rope I will cause the section C to slide up on the section B, so that as soon as the section B has been raised to its full height the section C will be found to have been raised to its full height above the section B. Thus it will be seen that (at a fire, for instance) time enough only is required to raise one section of a ladder divided into three sections, each of which 55 is necessarily shorter than a section of a ladder of the same length divided into two sections. Thus time is saved and the ladder shortened, the latter being an important advantage in transportation. 60

An ordinary ratchet, K, is provided for holding the ladder-sections in a raised position.

65 My improved folding crank consists of the main portion, L, placed upon the squared end of the shaft *e*, and the handle portion N, pivoted at *n* to said main portion. P is a spring secured at one end at *l* to the portion L, and provided at its other end with a projection, P', preferably rectangular in shape. That 70 end of the handle which is pivoted to the main portion is semicircular in shape, and is provided with two depressions, N' and N''. The depression N' is practically rectangular in shape, while the depression N'' has one 75 side cut away or rounded, as shown in Fig. 3. When the handle N is in position for use—that is to say, at right angles to the portion L—the projection P' lies in the opening N' and securely locks said handle, as shown in Fig. 80 85 3; but by lifting the free end of the spring P the projection P' is withdrawn from the depression N', and the handle N can be turned back and laid parallel with the portion L, in which position the projection P' lies in the depression N''. Inasmuch as it is desirable 90 that the handle should be capable of being placed in position for use without the slightest delay, one side of the depression N'' is, as above stated, cut away or rounded, so that although the pressure of the spring and projection P P' is sufficient to hold the handle closed, still, if force be applied to it, the said projection readily slips over the rounded portion between the depressions N'' N' and allows the handle to be swung up and locked in 95 100 the position shown in Fig. 3.

Having thus fully described my invention, what I claim, and desire to secure by Letters Patent, is—

In an extensible ladder, the combination, 5 with the hoisting mechanism thereof, of a crank mechanism consisting, essentially, of the main arm L, handle N, pivoted to said main arm and provided with the notches or de-

pressions N' N'', and the spring P, secured at one end to said main arm L, and provided near its free end with a projection, P', adapted to drop into said notches, substantially as and for the purpose described.

PELEG S. BRADFORD.
